F. J. WILKES,
METHOD OF MAKING BURGLAR ALARMS,
APPLICATION FILED DEC. 26, 1914.

UNITED STATES PATENT OFFICE.

FREDERICK J. WILKES, OF PHILADELPHIA, PENNSYLVANIA, ASSIGNOR TO DELIA M. WILKES.

METHOD OF MAKING BURGLAR-ALARMS.

1,183,262.

Specification of Letters Patent. Patented May 16, 1916.

Application filed December 26, 1914. Serial No. 879,220.

To all whom it may concern:

Be it known that I, FREDERICK J. WILKES, a citizen of the United States, and a resident of the city of Philadelphia, county of Philadelphia and State of Pennsylvania, have invented certain new and useful Improvements in the Method of Making Burglar-Alarms, of which the following is a full, clear, and exact disclosure.

10 The object of the invention is to provide an alarm of the class described, which is positive and thoroughly dependable in its operation, and of the lowest possible cost of manufacture.

5 Another object is to provide such an alarm which operates with an equal degree of efficiency on window or door, upon the former whether lowering the upper, or raising the lower, sash, and upon the latter regardless of whether it swings to the right or left.

Another object is to provide an alarm operative to fire a blank cartridge or detonating cap, by means of a spring actuated hammer, released by a door or sash operated trigger, the spring engaging only the rear end of said hammer and operating in alignment with the longitudinal axis thereof.

Still another object of the invention is to provide a method of manufacture of an alarm, which accomplishes all of the beneficial results of those previously placed on the market, but cuts the cost of production down to a relatively small fraction of that formerly experienced.

Heretofore, in the design and manufacture of alarms of this character it has been customary in general to provide a casting, which requires a considerable amount of machining, drilling, finishing, etc., and then is susceptible of being more or less easily broken or cracked (particularly when made of cast iron).

This invention, however, relates to the formation of the body portion of an alarm, comprising the base, cartridge support, plunger or hammer guide, and spring casing, from a one-piece metal punching, pressed into final shape by dies and with but two operations. Furthermore, aside from the fact that sheet metal punchings are much less expensive than castings in general and particularly so in this case, the finished device is much less liable to break when in the process of manufacture, while being shipped from place to place, and when in use on being sub-

jected to the sudden and severe shocks to which the same must from the very nature of its service and operation be subjected.

Further details as to the advantages and construction of the invention are fully 60 brought out in the following specification in which—

Figure 1 is a front elevation of the invention in its preferred embodiment as applied to the frame of a door-way; Fig. 2 is a similar view showing the relative positions of the parts of the device after having operated upon the opening of the door; Fig. 3 is a vertical sectional view of the device in operative position; Fig. 4 is a top plan view of 65 the same; Fig. 5 is a section on the line 5—5 of Fig. 3; Fig. 6 is a plan view of the blank from which the casing is formed; and Fig. 7 is a view showing the application of the device to an ordinary window sash. 75

Referring to the drawings, a door 10 is shown in Fig. 1 as closed and substantially filling the door-way or frame 11, to which latter is secured the device forming the subject of the present invention. In Fig. 2, the device is shown as having been operated by the opening of the door, thereby giving an audible signal or alarm by exploding the cartridge or detonating cap provided for this purpose. 80

The alarm device comprises a metal plate or punching such as that shown in Fig. 6, folded and bent in such manner as to form parallel, overlapping base portions 12 and 13, one being extended to form ears 14, 85 through which screws or other fastening means pass to maintain the device in a given position upon the desired object. Said base portions are bent upwardly and inwardly until they meet, whence they together form a support 15 for the outwardly extending substantially cylindrical looped portions 16, 17 and 18, these respectively comprising the spring casing, hammer guide and a cartridge support. The spring casing 16 is closed 90 at its upper end by means of radially inwardly bent V-shaped ears 19, while its lower end is open and separated from the hammer guide only by the transversely extending slot 20, in which oscillates the pin 100 or trigger 21 of the hammer 22, provided in turn with a firing point 23. 95

Within the cylindrical support 18 is placed a cartridge or the like 25, pointing 105 downwardly and prevented from slipping 110

therethrough by the coöperation of the flange 26 with the upper edge portion of the former. When set in position to operate, the respective parts of the device are 5 as shown in Fig. 1 with the trigger extended laterally into the path of the door, or window sash. Obviously, then, any opening of either of these members, throws said trigger around until the spring 30 is able to force 10 the hammer through the guide 17, as said trigger approaches the slanting part 31 of the slot leading into the longitudinally extending slot 32. Thereupon, the hammer is projected violently through its guide by 15 virtue of the coiled spring, until the movement of the firing point 23 is arrested by engagement with the priming cap of the cartridge, this impact being more than sufficient to explode the charge within the cartridge shell. From this position, the device 20 is reset by forcing the trigger back through the slot 32 until it reaches the transverse slot 20, whence it is oscillated to one side or the other.

25 As shown in Fig. 7, the embodiment of the invention as described above, may be readily applied to a window, to give an alarm when the same is opened after the device has been set. Preferably the alarm is secured upon 30 the upper face of the lower side 35 of the upper sash frame 36, and when set with the trigger 21 extending laterally into the path of the lower sash 37. Consequently, upon either lowering the upper, or raising the 35 lower sash, the alarm cartridge is exploded in the manner hereinbefore described.

Thus, I have provided a burglar alarm which entirely fulfils all the requirements placed upon it in a highly efficient manner.

But, even more so, I have invented a method 40 of manufacturing the same, which lessens the cost of manufacturing very considerably over any of those heretofore known and employed, and

Having fully described both the article 45 and the method of its manufacture, what I claim and desire to protect by Letters Patent of the United States is:

1. The method of making a casing for a 50 burglar alarm, which consists in pressing a metal blank to form a complete loop, the portions of said blank adjacent to said loop being brought together to form a supporting shank, thence being bent laterally outwardly in opposite directions, and one portion then being bent reversely one to overlap the other, to form a rigid base comprising three thicknesses of metal substantially throughout its transverse extent.

2. The method of making a casing for a 55 burglar alarm, which consists in pressing a metal blank to form a complete loop, the portions of said blank adjacent to said loop being brought together to form a supporting shank, thence being bent laterally outwardly in opposite directions, and one edge portion then being bent reversely to overlap the other reversely bent edge portion, to grip said second edge portion and prevent separation of the sides of said supporting shank, and to form a rigid base of three thicknesses.

In witness whereof, I have hereunto set my hand this 19th day of December, A. D., 1914.

FREDERICK J. WILKES.
